UNITED STATES PATENT OFFICE.

THOMAS BENN ELLWOOD, OF MARSHALL, TEXAS.

NAIL-DRIVING ATTACHMENT FOR AIR HAMMERS.

Application filed August 22, 1924, Serial No. 733,598.

To all whom it may concern:

Be it known that I, THOMAS BENN ELLWOOD, a citizen of the United States, residing at Marshall, in the county of Harrison and State of Texas, have invented certain new and useful Improvements in Nail-Driving Attachments for Air Hammers, of which the following is a specification.

This invention relates to nail driving devices, and has more particular reference to an attachment for air hammers whereby nails may be driven in a simple, efficient and ready manner, and without requiring the same to be struck by an ordinary hammer, which is almost an impossibility in certain inaccessible places, usually occasioned in the construction of frame buildings.

The primary object of my invention resides in the provision of a nail driving attachment which may be readily associated with air or other power hammers, and whereby nails may be driven in a quick manner, without requiring any unusual labor on the part of the worker.

A further object of my invention resides in the provision of a nail driving attachment for hammers that includes a hopper for the nails, together with means for automatically delivering the nails, one at a time, in a position to be encountered by the driving rod or bar of the attachment, which driving bar or rod is operated upon by the driving bullet or piston of the air or other power hammer.

An additional and important object is to provide an attachment of this character, wherein nails may be driven, vertically, horizontally, or at an incline in a simple and easy manner.

An additional object is to provide an attachment wherein the different parts thereof may be readily disassembled for repair, renewal or cleaning purposes.

With the foregoing and other objects in view, as the nature of the invention will be better understood, the same comprises the novel form, combination, and arrangement of parts hereinafter more fully described, shown in the accompanying drawings, and claimed.

In the drawings, wherein like reference characters indicate corresponding parts throughout the several views:

Figure 1 is a top plan view of an air hammer, with which is associated a nail driving attachment constructed in accordance with the present invention.

Figure 2 is a fragmentary side elevational view thereof.

Figure 3 is an enlarged fragmentary longitudinal sectional view of the attachment ⁶⁰ per se.

Figure 4 is an enlarged detail vertical sectional view, taken substantially upon the line 4—4 of Figure 2, for more clearly disclosing the nail hammer and the nail feeding means comprised in the present invention, and

Figure 5 is an elevational view of the nail carrier and guide that forms an essential part of the present invention. ⁷⁰

Now having particular reference to the drawing, and especially to Figures 1 and 2, there is shown a well known form of air hammer, designated generally 5, with which the present nail driving attachment may be ⁷⁵ associated.

It is, however, to be understood, that I do not wish to be limited to the association of my attachment with this particular type of gun, insomuch as in the future practice of ⁸⁰ the invention, minor changes may be made if necessary, to adapt the same to other forms of air hammers or power guns.

The invention, per se, constitutes the provision of an open ended cylinder 6 of a desired length that is formed upon its rear end and at diametrically opposite points with rearwardly extending outwardly diverging arms 7—7, the ends of which are formed with a coupling ring 8 whereby the attachment may be rigidly secured to the forward end of the barrel 5' of said air hammer 5, in a manner as clearly shown in said Figures 1 and 2. ⁸⁵

Upon the top side of said cylinder 6, and intermediate the ends thereof is formed a hopper 9, the forward wall of which is bowed outwardly as per Figure 4, while the rear wall thereof extends in a true vertical plane from a point slightly off center of the longitudinal axis of said cylinder 6, there being provided a restricted horizontal communicating passage 10, between said hopper and said cylinder, whereby the nails that are disposed within said hopper may pass one-by-one into the cylinder, and this, while the same are in a horizontal position when not prevented from doing this by a means hereinafter more fully described. ⁹⁵

The upper open end of the hopper 9 is ¹¹⁰ provided with a hinged lid 11, the forward edge of which normally enters the hopper

through the medium of the helical spring 12, included in the hinged construction for obviously forcing the nails downwardly within the hopper.

5 Disposed for free sliding horizontal movement and for a partial rotation within said cylinder 6, is a relatively elongated tube 13, that will hereinafter be referred to as a nail carrier. The bore 14 of the 10 rearmost half of said sleeve or nail carrier is of greater cross sectional area as indicated at 15, than the forward end of said bore for providing a shoulder 16 directly intermediate the ends of the bore of the 15 sleeve.

Extending within the beforementioned cylinder 6 as well as within the bore of the nail carrier 13 is the forward end of a horizontally disposed driving bar or rod 17, the 20 forward end of which terminates within the cylinder 6 for at all times engaging within the restricted forward end of the bore of said nail carrier for the purpose of providing a means for maintaining said bore in a 25 true horizontal position, as well as for other purposes, hereinafter to be more fully described.

The rear end of this driving bar or rod 17 is provided with a head 18, upon which is 30 formed a shank 19, of angular cross section that projects into the cylindrical end of the air hammer 5, whereby the air operated piston or bullet of said air hammer will contact therewith for actuating said 35 driving bar or rod in an obvious manner.

Surrounding the driving bar or rod intermediate the shoulder 16 of the nail carrier 13 and said head 18 is an expansible helical spring 20 that serves as a means for normally maintaining the nail carrier in the 40 position shown in Figures 1, 2, and 3, and for maintaining the shank of said driving bar or rod in position within the air hammer to be engaged by said air operated bullet or piston.

For limiting the longitudinal sliding movement of the carrier within the cylinder 6 of the attachment, said nail carrier is provided upon one side thereof and adjacent the bottom with a laterally extending pin 21 that extends through a longitudinal guide slot 22, formed at a similar point upon the cylinder 6, and intermediate the ends thereof as more clearly shown in 55 Figure 2.

The nail carrier 13 is formed at a point slightly offset with respect to the passageway 10, in the hopper 9 and cylinder 6, when said nail carrier is in an outwardly 60 normally extending position with a nail shaped slot 23, above the restricted area portion of the bore 14, and also at a point directly at the forward end of the enlarged area 15 of said bore, whereby, when said 65 nail carrier is slid rearwardly by pressure

of the same upon the work and slightly rotated in the manner hereinafter described, as to bring said nail shaped slot directly beneath the passageway 10, between said hopper 9 and cylinder 6, a single nail will 70 pass therethrough and rest upon the driving rod or bar 17, which at that time will be beneath said nail shaped slot, it being obvious that when pressure of the tool upon the work is released, the nail carrier will 75 move forwardly, under the action of the spring 20, whereupon the nail will then drop to a restricted portion of the bore 14, directly forwardly of the nail driving bar or rod 17, whereupon when the air is applied to the hammer 5, said bar or rod will be operated, for striking the nail, resulting in the driving of the same into the work. It will be readily appreciated by those skilled in the art, that during the driving 80 of the nail, the pressure of the tool upon the work will cause the rearward sliding movement of the nail carrier upon the cylinder 6. After one nail is driven, the release of pressure will occasion the presentation of another nail at a point as clearly 85 shown in Figure 3.

The rear end of the cylinder slot 22 is extended upwardly and rearwardly as at 90 24, Figure 2, whereby, when the pin 21 engages therein, a turning of the nail carrier 13 will be occasioned, for presenting the nail shaped slot directly beneath the passageway 10 between the hopper 9 and cylinder 6.

For preventing the passage of more than one nail into said nail shaped slot 23 of the nail carrier, there is provided a strip of spring metal 25, riveted or otherwise suitably secured at its upper end as at 26 to 95 the rear straight wall of the hopper 9. The lowermost end of this spring carrying a cross strip 27, the opposite ends of which are provided with inwardly extending lateral pins 28 that pass into said passageway 10, through the provision of openings 29, in the rear wall thereof. The strip 27 is formed intermediate its ends with a pendant curvilinear spring strip 28, that lies in close relation to the adjacent side of the cylinder 6; the lower end of this strip being formed at opposite sides with outturned ends 29, whereby the strip can be engaged by the before mentioned lug or pin 21 of the nail carrier means 13, in the raising of the strip in an outward direction with respect to the cylinder 6, for manifestly retracting the pin 28 in the opening 29, for allowing another nail to pass downwardly into the nail shaped slot of the nail carrier.

From the foregoing description, when considered in connection with the accompanying drawing, it will be apparent that I have provided a highly novel, simple and efficient form of nail driving attachment for 100

air and other power hammers, the use of which will result in the expeditious and accurate driving of nails, without requiring any undue labor upon the part of the operator.

Even though I have shown and described the most preferable embodiment of the present invention, it is nevertheless to be understood that minor changes may be made 10 therein without departing from the spirit and scope of the appended claims.

Having thus described my invention, what I claim as new and desire to secure by Letters Patent is:

15 1. In an attachment for power hammers of the character described, a cylinder having one end adapted for attachment to the usual cylinder end of the hammer, a hollow nail carrier longitudinally movable in 20 the cylinder, a nail hopper, means formed on said carrier for establishing communication between the hopper and carrier, and a driving rod extending at one end into the carrier and being adapted for insertion at 25 its other end within the cylinder of the hammer.

2. In an attachment for power hammers of the character described, a cylinder having one end adapted for attachment to the 30 usual cylinder end of the hammer, a hollow nail carrier longitudinally movable in the cylinder, a nail hopper, means formed on said carrier for establishing communication between the hopper and carrier, a driving 35 rod extending at one end into the carrier and being adapted for insertion at its other end within the cylinder of the hammer, and means for automatically feeding the nails from the hopper into the carrier.

40 3. In an attachment for power hammers of the character described, an open ended cylinder, means for securing the cylinder to the usual cylinder end of the hammer, a nail hopper formed upon the cylinder and 45 having communication therewith, a tubular shaped nail carrier longitudinally slidable within the cylinder, means on said carrier to receive a single nail from the hopper, and a driving rod extending at its forward 50 end within the carrier and adapted to be inserted at its opposite end within the cylinder of the carrier.

4. In an attachment for power hammers of the character described, an open ended 55 cylinder, means for securing the cylinder to the usual cylinder end of the hammer, a nail hopper formed upon the cylinder and having communication therewith, a tubular shaped nail carrier longitudinally slidable 60 within the cylinder, means on said carrier to receive a single nail from the hopper, a driving rod extending at its forward end

within the carrier and adapted to be inserted at its opposite end within the cylinder of the carrier, and automatic means for 65 regulating the passage of nails from the hopper into the carrier.

5. In an attachment for power hammers of the character described, an open ended cylinder, means for securing the cylinder 70 to the usual cylinder end of the hammer, a nail hopper formed upon the cylinder and having communication therewith, a tubular shaped nail carrier longitudinally slidable within the cylinder, means on said carrier 75 to receive a single nail from the hopper, a driving rod extending at its forward end within the carrier and adapted to be inserted at its opposite end within the cylinder of the carrier, and automatic means for 80 maintaining said end of the driving rod in the cylinder of the hammer.

6. In an attachment for power hammers of the character described, an open ended cylinder, means for securing the cylinder 85 to the usual cylinder end of the hammer, a nail hopper formed upon the cylinder and having communication therewith, a tubular shaped nail carrier longitudinally slidable within the cylinder, means on said carrier 90 to receive a single nail from the hopper, a driving rod extending at its forward end within the carrier and adapted to be inserted at its opposite end within the cylinder of the carrier, automatic means for 95 maintaining said end of the driving rod in the cylinder of the hammer and for maintaining the carrier in a position in which it is out of communication with the hopper.

7. An attachment for a pneumatic hammer comprising a nail receiving hopper having an intermediate restricted nail passage opening into a bottom cylinder, said cylinder being open at its opposite ends, a tubular nail carrier slidably mounted in 100 said cylinder, spring means for normally projecting the nail carrier to nail driving position, the extended portion of said carrier being provided with a nail shaped slot adapted to register with the aforesaid restricted passage, said slot being normally out 105 of alignment with said passage and being moved into alignment with the passage against tension of said spring means, a rod 110 extending from the hammer through one end of the cylinder and into said carrier, and attaching arms carried by the last named end of the cylinder and extending therefrom and adapted to be connected to the hammer.

In testimony whereof I affix my signature.

THOMAS BENN ELLWOOD.
